(57) **CLAIM**

The ornamental design for a fishing lure protective case as shown and described.

DESCRIPTION

FIG. 1 is a perspective view of the fishing lure protective case in an open configuration;

FIG. 2 is another perspective view of the fishing lure protective case in an open configuration;

FIG. 3 is a bottom plan view of the fishing lure protective case in an open configuration;

FIG. 4 is a top plan view of the fishing lure protective case in an open configuration;

FIG. 5 is a side elevation view of the fishing lure protective case in an open configuration;

FIG. 6 is another side elevation view of the fishing lure protective case in an open configuration;

FIG. 7 is a front elevation view of the fishing lure protective case in an open configuration;

FIG. 8 is a rear elevation view of the fishing lure protective case in an open configuration;

FIG. 9 is a perspective view of the fishing lure protective case in a closed configuration;

FIG. 10 is another perspective view of the fishing lure protective case in a closed configuration;

FIG. 11 is a top plan view of the fishing lure protective case in a closed configuration;

FIG. 12 is a bottom plan view of the fishing lure protective case in a closed configuration;

FIG. 13 is a side elevation view of the fishing lure protective case in a closed configuration;

FIG. 14 is another side elevation view of the fishing lure protective case in a closed configuration;

FIG. 15 is a front elevation view of the fishing lure protective case in a closed configuration; and,

FIG. 16 is a rear elevation view of the fishing lure protective case in a closed configuration.
